In Great Britain March 13, 1935

13 Claims. (CL 139—384)

This invention refers to webbing composed of two band-like lengths of woven material joined at intervals by cross tapes. One example of such webbing is that used in Venetian blinds, and another example is that called "pocket" tape, and used inside helmets for holding strips of cork or pith.

In weaving the webbing it is usual to weave the outer lengths of banding and the cross tapes as a simultaneous operation, portions of about $\frac{1}{2}$ " of each cross tape warps being interwoven with one of the bandings, and like portions of the cross tapes being interwoven with the other banding. In passing from one banding to the other, portions of about $\frac{1}{2}$ " of each of the cross tape warp threads are left free (without weft), as also a portion of about $1\frac{1}{2}$ " of the weft of each of such cross tapes, which "floats" from the rear end of one cross tape to the forward end of the next cross tape. That is to say, the free joining weft thread extends from the point where one cross tape begins to weave in with the outer banding web to where the binding of the next cross tape leaves off its binding and commences weaving separately as a cross tape, that is to say, the joining weft thread is longer than the warp joining threads to the extent of two bindings in and the length of the loose warp threads.

After the desired length of webbing has been woven and removed from the loom, the said free weftless joining warp threads and the $1\frac{1}{2}$ " of free weft are cut away, first by cutting across them at one end, and then by trimming off the severed free ends, four cuts in all for each adjacent pair of cross tapes. The operations of severing the connecting or joining free warp and weft threads and then trimming off the surplus ends (known in the trade as cutting and picking), entails a considerable amount of labour in the finishing off process of the webbing, and, therefore, adds considerably to the cost of production. Moreover, there is a considerable waste of material. Again, the cutting and picking involves the risk of accidentally cutting other parts of the webbing (making what are called "nibs") and consequent repair by sewing or darning.

This invention has for its object to weave the ladder webbing in a manner such that the lengths of the free weftless warp joining threads of the cross tapes are reduced to a minimum, or so that the end of one binding-in is practically contiguous with the beginning of the next, whilst the usually floating joining weft thread is caused to engage in the binding in of the cross tapes, and to be completely absorbed until it recommences

its function of weaving the next cross tape, the otherwise free weft thread starting and finishing its "float" with the unbound weftless portion of the warp threads. In this way, only very short lengths of free warps and weft will be left between the bindings in of the cross tapes and the outer bandings, and one cut (instead of several cuts) will be sufficient to effect the complete severance of each of the free warp and weft connections between the outer bandings. Moreover, the bindings in will be of a longer length than heretofore, and the webbing, as a whole, will consequently be stronger, which, especially in the case of small sizes of webbing, will ensure of the cross tapes being better able to carry the blind slats or laths.

Hitherto, the webbing has been woven in a loom provided with a jacquard or dobby to control the healds carrying the cross tape warp threads, such jacquard or dobby motion causing the cross tape warps to rest or "float" for a distance between the woven-in cross tapes, in order to prevent bulging of the selvedges of the outer banding webs, and also to prevent trapping (causing "loops" or "purls") of the weft in the outer banding webs. Such resting or "floating" of the cross tape warps, however, has caused a considerable portion of the warps to be unwoven at the time of passing from one outer banding web to the other, and thus leave the aforesaid objectionable lengths of weftless warp threads. Further, the free cross tape weft has, for a like reason, extended from the commencement of one cross tape binding-in to the finish of the next binding-in on the surface of the banding web.

According to the invention, the weaving of the improved webbing is effected in a multi-slot narrow tape loom fitted with either a dobby or jacquard. In the case of a dobby, such dobby is given a positive lifting motion whereby the movements of the healds are rendered positive and smoother, without causing bulging of the selvedge of the banding webs, and without looping or purling of the weft, and, therefore, reducing to a minimum the lengths of unwoven warp threads between the bindings in of the cross tape threads and the outer banding webs, and further, enabling the heretofore floating weft of the said cross tapes to be woven into the banding webs at the same time as the interweaving of the strap warp threads with the said banding webs. In the case of a jacquard, the ratio of movement between the jacquard-operating shaft and the intermediate jack or chain operating mechanism is adjusted so that a quicker heald-lifting and slower return

motion is obtained. Further, the pattern cards are designed, during what is known as the "rest" or "dwell" periods, to weave the hitherto floating weft into the bindings-in.

5 By either of the before-named methods, the improved webbing is effectively and expeditiously produced with the lengths of unwoven warp threads between the cross tapes and webs reduced to such an extent that no trimming is required 10 after once cutting through the threads, and the hitherto loose wefts between adjacent bindings-in are interwoven with the webbing. Another advantage is that each binding in of the cross tapes is longer than previously, thus making the webbing as a whole much stronger than heretofore.

15 The invention may be applied to webbing, the cross tapes of which consist of warp threads only, and also to webbing with pairs of cross tapes (woven or weftless) arranged side by side. It 20 may also be applied to webbing having three rows of cross tapes, one row near to one edge, another row near to the other edge of the webbing, and a third row central to the width of the webbing.

25 In the weaving of ladder or like webbing, the webbing passes through a device called a "stopper" which serves to support and guide the webbing as it passes forward to the breast beam and to its take-up and delivery rollers at the front of the loom and into the work box.

30 The known "stopper" consists of a stout metal rod, bent at right angles to its length at one end to form an open-ended U-shaped loop, through which the webbing passes and at another part fixed to the breast beam of the loom. Such known 35 stopper has several drawbacks, but mainly that it allows the webs to work out through the open side of the loop, thus causing bad weaving, as well as allowing the webs to project beyond the width of the slot in the loom batten, such drawbacks 40 also causing long stoppages of the loom to correct the weave. A further drawback is that the loop part of the stopper does not hold the webs close together, especially at the time and point of the beat up, which results in slack weaving and, in 45 the case of ladder and like webbing, results in the aforesaid excessive portions of the warp threads of the cross tapes being left unwoven, and necessitating the subsequent cutting away or trimming by hand of the surplus warp threads 50 when separating the outer bandings from each other. A further fault of the known "stopper" is that it is only supported at one side, and its opposite side is free to move and get out of line with the loom batten. It is also incapable of yielding 55 bodily if and when struck by the loom batten.

60 A further object of this invention is a construction of "stopper" and stopper-supporting means by which the foregoing drawbacks are eliminated.

60 In the accompanying drawings:

Fig. 1 illustrates a portion of the improved ladder webbing as it appears when in use.

Fig. 2 illustrates an edge view, and

65 Fig. 3 a plan view (with the top banding removed) of a short length of the known webbing, prior to severing the relatively long unwoven warp threads between each binding in and the outer bandings, and prior to severing the long unwoven weft threads between successive cross 70 tapes.

75 Fig. 4 illustrates an edge view of a short length of the improved webbing prior to severing the short unwoven warp threads between the bindings in and the short single weft thread. Such view also illustrates how the bindings in are longer

than theretofore, and thereby strengthen the webbing.

Fig. 5 illustrates a plan of Fig. 4 with the top banding removed.

Fig. 6 illustrates a plan of the improved webbing 5 (with the top banding removed) when made with unwoven cross tapes, i. e., cross tapes composed only of warp threads.

Fig. 7 illustrates an edge view of the improved ladder webbing when provided with pairs of cross 10 tapes for each blind lath.

Fig. 8 illustrates a like plan view of webbing having cross tapes along each edge and central to its width.

Fig. 9 illustrates a plan view,

Fig. 9a a cross section, and

Figs. 10 a perspective view of one example of the improved web-supporting and guiding "stopper".

Fig. 11 illustrates in perspective a further example, and Fig. 12 a plan view of a modification of the stopper-supporting devices.

Referring to Fig. 1, a, a are the two outer lengths of webbing, and b, b the series of cross tapes, these latter lying alternately alongside the 25 opposite edges of the webbing.

As shown in Figs. 2 and 3, in the ordinary make of webbing relatively long lengths of unwoven warp threads c are left between the binding in b¹ of the end of one cross tape to one length of 30 webbing, and the binding in b² of the end of the next cross tape to the other length of webbing along the same edge of the webbing. Also, a relatively long length of unwoven weft d extends from the start of one binding in to the finish of 35 the next binding in. As aforesaid, the cutting away of such free warp and weft, first to separate the two webbings, and then to give a neat finish to the webbing, entails a considerable amount of time and labour.

40 In the improved webbing, as shown in Figs. 4 and 5, the unwoven portions c of the warp between each binding in is comparatively short, and in fact, is so short that one cut is sufficient, both for severing and trimming. Further, there is no free weft thread to sever, since the weft is woven into the bindings in.

45 As showing the saving in the labour of finishing the improved webbing, it may be pointed out that with the old make of webbing having 24 cross 50 tapes to the yard (12 on each side), and each cross tape requiring 4 cuts to separate the bandings and remove the ends of the free warp and weft threads, no less than 13,824 cuts will be necessary in a webbing 144 yards long, whereas 55 with the improved webbing of the same length and having the same number of cross tapes, the total number of cuts will only amount to 3,456.

As aforesaid, the invention may be used in the production of webbing having weftless cross 60 tapes, see Fig. 6, each cross tape consisting of warp threads only, and the weft used for binding in passing into the outer banding after each binding in.

65 The invention may also be applied in the production of webbing having pairs of cross tapes, see Fig. 7, near to the respective edges of the outer banding, and one slightly in advance of the other, so that when the webbing is in use, a lath may be inserted between each pair of adjacent cross 70 tapes. It may also be applied to webbing having a central row of cross tapes in addition to the cross tapes near to the edges of the webbing, see Fig. 8. In all cases, the cross tapes may each be 75 weftless, or otherwise.

5 Referring now to Figs. 9, 9a and 10, which show an example of the improved "stopper" and stopper-supporting means, the "stopper" is composed of a metal or other hard block *e* of elongated and flat formation and having an elongated slot *e*¹, also having two socket holes *e*², by which the "stopper" is fitted on to and carried horizontally by two rods *f*¹, *f*² secured to and extending from the breast piece *g* of the loom.

10 The two webs, as they are woven, pass through the "stopper" from the heald side, and thence over the breast piece to the take-up and delivery rollers and work box.

15 With the "stopper" fitted to and held by the rods *f*¹, *f*² in a position such that its forward longitudinal side lies near to the "fells" of the webs and with the slot *e*¹ comparatively narrow and its upper and lower sides flat and parallel, it holds the two webs firmly and closely together 20 during each beat-up of the weft, which results in tighter weaving.

25 To permit of the webs being removed from the "stopper" without disturbing their connection with the take-up roller, say when requiring to inspect the inside or underside of the webs, the upper thickness of the stopper may, as shown in Fig. 11, be formed with an opening *e*³ preferably diagonal, through which the webs may be withdrawn, and through which they may be passed 30 back again into the "stopper" after inspection. Alternatively, the "stopper" may be removed bodily from the rods *f*¹, *f*² and slid along the webs. The opening *e*³ in the "stopper" also allows 35 of the "stopper" being used to anchor the loose weft after reshuttling and the broken warp ends after being drawn in.

40 To afford a yielding contact of the "stopper" if and when struck by the loom batten, the rods *f*¹, *f*² may be fitted with coiled springs, see Fig. 12, which yield on the "stopper" being struck by the batten, but otherwise hold it in its normal forward position.

45 By reason of the slot *e*¹ in the "stopper" being closed at the ends next the sides of the "stopper", the webs cannot leave the "stopper" sideways, as in the known "stopper".

50 Lastly, it will be seen that by reason of the tighter weaving of the webbing due to the altered heald motions, the increase in the length of each binding in, the reduction in length of the loose warps and weft between the bindings in, and the firmer hold on the webbing at the "fells", a much firmer and stronger construction of webbing is obtained. In addition to such advantages, a 55 great saving is effected in the subsequent finishing (cutting) operations.

55 By the term "stitching area" as used in the claims, it is intended to include the area of interconnection or binding-in of a cross-tape and an outer band. The term "cross straps" is intended to be synonymous with the term "cross tapes", and the term "main tapes" is synonymous with "outer bands". The term "filling thread" is synonymous with the term "weft thread".

60 What I claim is:

1. Ladder webbing and the like comprising two outer bands and a series of cross-tapes woven into said bands, said cross-tapes including a plurality of warp threads woven alternately into one and 65 then the other of said outer bands, the distance between the ending of the aforesaid weaving-in of said warp threads on the first band and the beginning of the weaving-in on the second band being so short as to make said ending and said 70 beginning substantially contiguous.

2. Ladder webbing and the like comprising two outer bands and a series of cross-tapes woven into said bands, said cross-tapes including a plurality of warp threads woven alternately into one and then the other of said outer bands, the distance between the ending of the weaving-in on the first band and the beginning of the aforesaid weaving-in of said warp threads on the second band being so short as to make said ending and said beginning substantially contiguous, said 75 interconnection between said bands having been snipped through.

3. Ladder webbing and the like comprising two outer bands and a series of cross-tapes woven into said bands, said cross-tapes including a plurality of warp threads woven alternately into one and then the other of said outer bands, the distance between the ending of the aforesaid weaving-in of said warp threads on the first band and the beginning of the weaving-in on the second band 80 being so short as to make said ending and said beginning substantially contiguous, said interconnection between said bands having been snipped through, so that when the ladder webbing is collapsed said beginning and ending meet. 25

4. Ladder webbing and the like comprising two outer bands and a series of cross-tapes woven into said bands, said cross-tapes including a plurality of warp threads woven alternately into one and then the other of said outer bands, a weft 30 thread woven into the warp to form woven cross-tapes, the distance between the ending of the aforesaid weaving-in of said warp threads on the first band and the beginning of the weaving-in on the second band being so short as to make 35 said ending and said beginning substantially contiguous.

5. Ladder webbing and the like comprising two outer bands and a series of cross-tapes woven into said bands, said cross-tapes including a plurality of warp threads woven alternately into one and then the other of said outer bands, a weft thread 40 woven into the warp to form woven cross-tapes, the distance between the ending of the aforesaid weaving-in of said warp threads on the first band and the beginning of the weaving-in on the second band being so short as to make said ending and said beginning substantially contiguous, said 45 weft thread being also woven into said outer bands with said warp threads. 50

6. The method of weaving ladder web for Venetian blinds having a pair of main tapes and interconnecting cross straps, which comprises interweaving the filling thread of a strap with the warp threads of said strap within a stitching area where said warp threads are interwoven with the filling thread of a main tape of the web. 55

7. The method of weaving ladder web for Venetian blinds having a pair of main tapes and 60 interconnecting cross straps, which comprises interweaving the filling thread of a strap with the warp threads of said strap within a stitching area where said warp threads are interwoven with the filling thread of a main tape of the web; 65 said interweaving of the strap filling thread being located close-by where the strap warp threads float between the main tapes.

8. The method of weaving ladder web for Venetian blinds having a pair of main tapes and 70 interconnecting cross straps which comprises binding the filling thread of a strap to a main tape so that upon severing the floating warp threads of the strap the said filling thread will be simultaneously severed leaving ends substan- 75

tially the same length as the severed ends of the warp threads.

9. Ladder web for Venetian blinds comprising a pair of main tapes and interconnecting cross straps having a stitching area within which the filling thread of a strap is interwoven with the warp threads of a strap where such warp threads are also interwoven with the filling thread of a main tape.
10. Ladder web for Venetian blinds comprising main tapes and interconnecting cross straps having a stitching area within which the filling thread of a strap is interwoven with the warp threads of said strap where said warp threads are interwoven with the filling thread of a main tape.
11. Ladder web for Venetian blinds comprising main tapes and interconnecting cross straps having a stitching area within which the filling thread of a strap is interwoven with the warp threads of said strap where said warp threads are interwoven with the filling thread of a main tape.

11. A method of forming ladder webbing and the like which comprises weaving two outer bands in substantially contiguous relation, providing at least one set of additional warp threads which form cross-tapes, said warp threads passing through a heald, regulating the movements of said heald to cause said warp threads to be woven-in alternately into the first and then the second of said outer bands to form cross-tapes, said heald being quickly shifted at the end of one weaving-in so that the next weaving-in starts with practically no loss of time and leaves only an extremely short connection between said successive weavings-in.

12. A method of forming ladder webbing and

the like which comprises weaving two outer bands in substantially contiguous relation, providing at least one set of additional warp threads which form cross-tapes, an additional weft thread for said cross-tapes, said warp threads passing through a heald, regulating the movements of said heald to cause said warp threads to be woven-in alternately into the first and then the second of said outer bands to form cross-tapes, said heald being quickly shifted at the end of one weaving-in so that the next weaving-in starts with practically no loss of time and leaves only an extremely short connection between said successive weavings-in. 5 10

13. A method of forming ladder webbing and the like which comprises weaving two outer bands in substantially contiguous relation, providing at least one set of additional warp threads which form cross-tapes, an additional weft thread for said cross tapes, said warp threads passing through a heald, regulating the movements of said heald to cause said warp threads to be woven-in alternately into the first and then the second of said outer bands to form cross-tapes, said heald being quickly shifted at the end of one weaving-in so that the next weaving-in starts with practically no loss of time and leaves only an extremely short connection between successive weavings-in, and weaving said weft thread into the outer bands with said warp threads. 30
